FIG. 1 is a rear, right perspective view of a sock insert pocket showing our new design;

FIG. 2 is a front view thereof;

FIG. 3 is a rear view thereof;

FIG. 4 is a left-side view thereof;

FIG. 5 is a right-side view thereof

FIG. 6 is a top view thereof;

FIG. 7 is a bottom view thereof;

FIG. 8 is a rear, right perspective view of a sock insert as would be placed in the sock insert pocket of our new design;

FIG. 9 is a front view thereof;

FIG. 10 is a bottom view thereof; and,

FIG. 11 is a side view thereof.

The portions of the drawings shown in broken lines indicate surrounding structure and environment that forms no part of the claimed design.
